Trademark Serial No. 85700010, Apple Inc., filed Aug. 9, 2012, priority date Feb. 15, 2012.

Primary Examiner — Philip S. Hyder*Assistant Examiner* — Darlington Ly(74) *Attorney, Agent, or Firm* — Sterne, Kessler, Goldstein & Fox, P.L.L.C.(57) **CLAIM**

The ornamental design for a display screen or portion thereof with graphical user interface, as shown and described.

DESCRIPTION

The patent or application file contains at least one drawing executed in color. Copies of this patent or patent application publication with color drawing(s) will be provided by the Office upon request and payment of the necessary fee.

FIG. 1 is a front view of a display screen or portion thereof with a graphical user interface showing my new design;

FIG. 2 is a front view of a display screen or portion thereof with a graphical user interface showing my new design;

FIG. 3 is a front view of a display screen or portion thereof with a graphical user interface showing my new design; and,

FIG. 4 is a front view of a display screen or portion thereof with a graphical user interface showing my new design.

The dashed broken lines around the figures show a display screen or portion thereof that form no part of the claimed design. The dot-dash broken lines and the areas within the dot-dash broken lines form no part of the claimed design.
